CLINTON WALLACE HOUGH, OF NEW YORK, N. Y., ASSIGNOR TO WIRED RADIO, INC.,
OF NEW YORK, N. Y., A CORPORATION OF DELAWARE

POLYPHASE PHOTO-ELECTRIC DEVICE

Application filed December 27, 1930. Serial No. 505,057.

This invention pertains in general to photosensitive devices and specifically relates to a photosensitive device for producing polyphase current.

One of the objects of my invention consists in providing a photoelectric device for producing photoelectric currents in polyphase relation.

10 Another object consists in producing a photosensitive device having a plurality of cathodes interconnected in polyphase relation.

I accomplish the above desirable objects 15 in a novel type of photoelectric cell having an anode and a plurality of cathodes contained within an envelope and connected to a polyphase circuit.

In the drawing which accompanies and 20 forms a part of this specification and in which like reference numerals designate corresponding parts throughout:

Fig. 1 is a sectional view of one embodiment of the photoelectric device of my invention;

25 Fig. 2 is a sectional view along the line 2—2 of Fig. 1; and

Fig. 3 is a schematic representation of the system of my invention for producing 30 polyphase current and which utilizes the photoelectric device shown in Fig. 1.

In my Patent 1,886,188, issued November 1, 1932, I have disclosed a system for producing polyphase current by means of a 35 rotating aperture disk which interrupts irradiations incident upon a plurality of photoelectric cells interconnected in polyphase relation. My present invention is directed to providing a unitary construction of a 40 photoelectric device having a plurality of photosensitive cathodes and a single anode within the same containing envelope employed in conjunction with a polyphase circuit. Light directed upon these cathodes in 45 polyphase time relation will, therefore, produce polyphase current in accordance with my invention.

Referring to the drawing in detail, and particularly to Fig. 1, I provide an envelope 50 1 composed of a suitable transparent mate-

rial such as glass or fused quartz. This envelope is evacuated to provide an attenuated atmosphere within suitable for producing electronic discharges. Three cathodes 2, 3, and 4 are mounted upon terminal connections 5, 6, and 7 which extend through the walls of the envelope 1, as shown. These cathodes are composed of a suitable metallic material such as nickel and are coated upon their interior surfaces with a photosensitive element such as potassium or caesium. A tubular anode 8 is positioned within the envelope 1 at approximately the center of the radius of the cylindrical surfaces formed by the cathodes 2, 3, and 4. When proper potentials are applied to the cathodes 2, 3, and 4, and the anode 8, irradiations directed upon the photosensitive surface of the cathodes 2, 3, and 4 will produce photoelectric emission to the anode 8. This photoelectric emission to the anode 8 will be substantially proportional to the intensity of the irradiations incident upon the cathodes. The foregoing constitutes the construction 75 of photoelectric cell employed in the system of my invention. It is, of course, to be understood that the number of cathodes can be varied to produce various number of phases.

According to my invention, the envelope 1, in Fig. 3, is disposed in the path of irradiations from a lamp 9 which is positioned in front of a parabolic reflector 10. The lamp 9 in the present embodiment of my invention is of the incandescent type and is connected to a source of current 11. However, any suitable source of irradiations may be substituted for the lamp 9. A disk 12 is interposed between the lamp 9 and the envelope 1. This disk is opaque and is provided with an annular series of apertures adapted to periodically admit light rays from the lamp 9 to the envelope 1 when the disk is rotated. An aperture plate 13 is positioned between the disk 12 and the envelope 1. This aperture plate is opaque but is provided with three apertures which define three beams of light which are respectively incident upon the three cathodes within the envelope 1.

The apertures in the plate 13 are so disposed with reference to the apparatus in the disk 12 that, when the disk 12 is rotated, the instants of greatest illumination of the respective cathodes will be displaced from each other, with respect to time, in polyphase relation. That is, the photoelectric currents produced by each of the cathodes will reach a maximum value at different time intervals in polyphase relation. This is accomplished as in my heretofore mentioned patent by disposing the apertures in the plate 13 with relation to the series of apertures in the disk 12 in a manner such that when the lower aperture in the plate 13 is in full engagement with one of the apertures in the disk 12, the middle aperture in the plate 13 is displaced from full engagement with another one of the apertures in the disk 12 by an arcuate distance equal to two-thirds the diameter of any aperture in the disk 12 and further, the topmost aperture in the plate 13 is displaced from the next successive aperture in the disk 12, through which light from the source 9 will be transmitted through the topmost aperture in the plate 13, by one and one-third times the diameter of any aperture in the disk 12. Preferably the apertures in the disk 12 are so placed therein that the arcuate space between each aperture is equal to the diameter of any of the apertures. In this manner, when the disk 12 is rotated in the direction of the arrow thereon, light impulses will be transmitted through the disk 12 and the plate 13 in proper time sequence to produce through the agency of the photoelectric cell 1 and its associated thermionic tubes and circuits polyphase currents in the output circuits of the thermionic tubes. It is to be understood that the mechanical arrangement of the parts shown in Fig. 3 is purely elementary and not intended to denote mechanical construction. The exact arrangement of mechanical parts for producing successive excitation of photosensitive cathodes in polyphase relation is disclosed in greater detail in my patent before referred to.

The anode 8 is connected through a source of high potential 14 to the filaments of three space discharge amplifiers 15, 16, and 17, as shown. The cathodes 2, 3, and 4 are respectively connected through the electrostatic condensers 18, 19, and 20 to the grids of the space discharge amplifiers 15, 16, and 17. Resistances 21, 22, and 23 are provided across the input circuit of each of the space discharge amplifiers. The plate of the space discharge amplifiers 15, 16, and 17 are respectively connected to three inductances 24, 25, and 26 which are interconnected in Y-formation at a common point 27. A connection is provided from the point 27 through a source of high potential 28 to all of the filaments of the space discharge amplifiers 15,

16, and 17. Three other inductances 29, 30 and 31 are interconnected in Y-formation at a common point 32 and are electromagnetically coupled to the inductances 24, 25, and 26, respectively. The inductances 29, 30, 76 and 31 comprise a work circuit for utilization of the polyphase current produced according to my system.

The photoelectric currents produced in polyphase relation by the cathodes 2, 3, and 4 are respectively amplified by the space discharge amplifiers 15, 16, and 17. The outputs of these amplifiers then energize the inductances 24, 25, and 26 to induce three-phase current in the work circuits 29, 30, and 80 31. The light intensity from the lamp 9 can be varied, if desired, in accordance with voice modulating currents and thereby effect modulation of the three-phase current produced by my system. 85

It will now be evident that I have provided a unitary photosensitive device adapted to produce polyphase current by photosensitive means in a simple and efficient manner. It is, of course, to be understood that changes in my polyphase photoelectric device may be made but which will not depart from the intended scope of my invention. I do not, therefore, desire to limit myself to the foregoing except insofar as 95 may be pointed out in the appended claims.

What I claim as new and original and desire to secure by Letters Patent of the United States is:

1. A polyphase photoelectric system comprising, an evacuated envelope, an anode positioned in said envelope, a plurality of photosensitive cathodes positioned in said envelope, and a polyphase circuit interconnecting said cathodes. 100 105

2. The combination of an evacuated envelope, an anode within said envelope, a plurality of photosensitive cathodes within said envelope, a space discharge amplifier connected to each of said cathodes, and an output circuit for each of said space discharge amplifiers, said output circuits being interconnected in polyphase relation. 110

3. The combination of an evacuated envelope, an anode within said envelope, a plurality of photosensitive cathodes within said envelope, a common source of current for energizing all of said cathodes, a plurality of space discharge tubes each of which is under control of one of said cathodes, and a plurality of inductances each of which is adapted to be energized by a different one of said space discharge tubes, said inductances being interconnected in polyphase relation. 115 120 125

4. The combination with a plurality of space discharge tubes each having a grid, plate, and a filament, of an evacuated envelope, an anode within said envelope and connected to all of said filaments, a plu- 130

rality of photosensitive cathodes within said envelope, each of said cathodes being connected to one of said grids; and a polyphase output circuit interconnecting said plates.

5. The combination with a plurality of space discharge tubes each having an anode, a grid, and a filament, of an evacuated envelope, an anode within said envelope and connected to all of said filaments, a plurality of photosensitive cathodes within said envelope, each of said cathodes being connected to one of said grids, and a plurality of inductances each of which is connected to 10 one of said anodes, said inductances being interconnected in polyphase relation.
